UNITED STATES PATENT OFFICE.

CHARLES S. HANNA, OF WEST HEBRON, NEW YORK.

DESIGN FOR A CREAM-SEPARATOR.

SPECIFICATION forming part of Design No. 31,255, dated July 18, 1899.

Application filed June 24, 1899. Serial No. 721,787. Term of patent 7 years.

To all whom it may concern:

Be it known that I, CHARLES S. HANNA, of West Hebron, in the county of Washington and State of New York, have invented and 5 produced a new and original Design for a Cream-Separator, of which the following is a full, clear, and exact description.

Reference is to be had to the accompanying drawings, forming a part of this specification, 10 in which similar characters of reference indicate corresponding parts in all the views.

Figure 1 is a front elevation of a cream-separator, showing my design. Fig. 2 is a 15 sectional side elevation of the same on the line 2-2 in Fig. 3, and Fig. 3 is a sectional plan view of the same on the line 3-3 in Fig. 1.

The design in its entirety consists of a cylindrical body A, having its lower end terminating in an offset base B, and a bottom C, in 20 the form of an inverted cone, the base of the

cone bottom joining the body at the beginning of the offset B, the apex of the cone bottom appearing ornamented and having a cylinder-gage D, and a faucet E at the end of the cylinder, the upper end of the body appearing with oppositely-arranged handles F and a ring G, terminating in a handle G' at the front of said body. 25

The leading feature of the design consists of a body A having a base and an inverted 30 cone-shaped bottom terminating at its apex in a gage, with a faucet.

I claim—

The design for a cream-separator herein shown and described.

CHARLES S. HANNA.
